(57)

CLAIM

The ornamental design for a shoe as shown and described.

DESCRIPTION

The sole FIGURE is a bottom view of a shoe showing our new design.

The broken lines in the FIGURE show portions of the shoe that form no part of the claimed design.

1 Claim, 1 Drawing Sheet

Related U.S. Application Data

is a continuation of application No. 29/784,877, filed on May 21, 2021, now Pat. No. Des. 989,446.
